UNITED STATES PATENT OFFICE.

THOMAS KEPPEL NORTH, OF WESTMINSTER, LONDON, ENGLAND, ASSIGNOR TO VICKERS
LIMITED, OF WESTMINSTER, ENGLAND.

SUBMARINE MINE.

1,299,012.

Specification of Letters Patent.

Patented Apr. 1, 1919.

Application filed June 21, 1917. Serial No. 176,064.

To all whom it may concern:

Be it known that I, THOMAS KEPPEL NORTH, a subject of the King of Great Britain, residing at Vickers House, Broad-
5 way, Westminster, in the county of London, England, have invented certain new and useful Improvements in or Relating to Sub-
marine Mines, of which the following is a specification.

10 This invention relates to submarine mines of the kind comprising a flotation chamber, constituting the mine proper, an anchor containing a drum on which is wound a cable connecting the anchor to the flotation chamber and a plummet or sounding ball controlling a ratchet pawl adapted to engage with ratchet teeth on the cable drum of the anchor; this plummet holds the ratchet pawl out of engagement with the ratchet teeth
15 during the descent of the anchor in the water thereby enabling the cable drum to unwind, but when the plummet touches the sea bed the said pawl is caused to engage with the ratchet teeth and the anchor then draws the flotation chamber beneath the surface of the water till it assumes a depth predetermined by the effective length of the plummet line.

According to the present invention the pawl is retained in its disengaged position
20 by a spring controlled trigger or sear which is held in engagement with the pawl by the weight of the plummet; when the plummet reaches the sea bed the trigger is moved by its spring into its disengaged position and a spring operating upon the pawl moves the latter into engagement with the ratchet teeth on the anchor cable drum. The said trigger is so constructed that if the weight of the plummet is again exerted upon it, a portion
25 thereof will engage with the pawl and retain it all the more firmly in engagement with the ratchet teeth. It will thus be seen that there is no possibility of the pawl becoming disengaged from the ratchet teeth as a result of a pull being exerted upon the plummet line after the plummet has reached the sea bed.

In order that the said invention may be clearly understood and readily carried into effect, the same will be described more fully with reference to the accompanying drawings, in which:—

Figures 1, 2 and 3 are respectively a sec-
tional side elevation, a sectional end eleva-

tion and a plan of a constructional form of 55
the improvements,

Figs. 4, 5 and 6 are diagrams showing the essential parts of the improvements in three different positions hereinafter referred to, and

60 Fig. 7 is a sectional elevation showing the "anti-vibration device" hereinafter referred to, the parts of this device being shown in the position to allow the pawl to move into engagement with the ratchet teeth on the anchor cable drum, and Figs. 8 and 9 are respectively a sectional side elevation and a sectional end elevation showing the improvements in position on a mine.

A is the ratchet pawl and A', A' are the 70 ratchet teeth of the anchor cable drum A^x (Fig. 9) with which the said pawl is adapted to engage. B is the aforesaid spring controlled trigger or sear connected to the line B^x of the plummet B^{xx} (Fig. 9) by a link B'. 75

In the example shown the pawl A, its spring a, the trigger B and its spring b are all carried upon a plate or bracket C to which the pawl and the trigger are pivoted at a^x, b^x respectively. The pawl A is provided with a lateral pin A² in the path of which normally lies a plunger D forming part of a so-called "anti-vibration device" for preventing movement of the pawl into engagement with the ratchet teeth until the anchor cable drum has made a predetermined number of revolutions. This pin is formed with a flat face a² for engagement with the nose B² of the trigger B. 80 85

The said "anti-vibration device" is well 90 known and comprises a nut D' mounted on the screw-threaded end of the shaft A^{xx} to which the drum A^x is connected, the said nut, prior to the launching of the mine, occupying the position shown by Fig. 9 in 95 which it blocks the movement of the plunger D away from the pin A². The nut D is prevented from rotating but is free to move axially so that as the drum rotates the nut is gradually moved into the position shown 100 by Fig. 7 in which the plunger D is free to be moved by its spring away from the pin A². The spring a can then shift the pawl B into the position shown by Fig. 4 with the face a² in contact with the nose B² of the 105 trigger. When the plummet reaches the sea bed and no longer exerts a pull on the trigger B, the spring b displaces the said

- trigger into the position shown by Fig. 5 to release the pawl A which is then moved by its spring a into engagement with the ratchet teeth A', A' as shown by Fig. 5.
- 5 In the event of a further pull being exerted upon the plummet line the trigger will be displaced into the position shown in Fig. 6 in which an inclined flat surface b^s on the nose B ^{s} bears against a corresponding surface a^s on the pawl A so that instead of tending to disengage the latter it will operate to more firmly retain the said pawl in engagement with the ratchet teeth A', A' as aforesaid.
- 10 15 What I claim and desire to secure by Letters Patent of the United States is:—
1. In a submarine mine comprising a flotation chamber constituting the mine proper, an anchor cable drum and a plummet for determining the depth at which the flotation chamber is to be anchored beneath the surface of the water, the combination of a member for engaging with the said drum, and a retaining device which is connected to the plummet and holds said member out of engagement with the drum until the plummet touches the sea bed.
  2. In a submarine mine comprising a flotation chamber constituting the mine proper, a toothed anchor cable drum and a plummet for determining the depth at which the flotation chamber is to be anchored beneath the surface of the water, the combination of a spring controlled pawl for engaging with the teeth of said drum, and a spring controlled trigger which is adapted to engage with the pawl and is connected to the plummet.
  3. In a submarine mine comprising a flotation chamber constituting the mine proper, an anchor cable drum and a plummet for determining the depth at which the flotation chamber is to be anchored beneath the surface of the water, the combination of a member for engaging with the said drum, a retaining device which is connected to the plummet and holds said member out of engagement with the drum until the plummet touches the sea bed, and means whereby, if a pull should again be exerted upon the retaining device after the member has moved into engagement with the drum, the said device will operate to hold the member all the more firmly in engagement with the drum.
  4. In a submarine mine comprising a flotation chamber constituting the mine proper, a toothed anchor cable drum and a plummet

for determining the depth at which the flotation chamber is to be anchored beneath the surface of the water, the combination of a spring controlled pawl for engaging with the teeth of said drum, a spring controlled trigger which is adapted to engage with the pawl and is connected to the plummet, and means whereby, if a pull should again be exerted upon the trigger after the pawl has moved into engagement with the teeth, the trigger will operate to hold the pawl all the more firmly in engagement with the drum.

5. In a submarine mine comprising a flotation chamber constituting the mine proper, a toothed anchor cable drum and a plummet for determining the depth at which the flotation chamber is to be anchored beneath the surface of the water, the combination of a spring controlled pawl for engaging with the teeth of said drum, a lateral projection on said pawl, a spring controlled trigger which is connected to the plummet and has a nose for engaging with part of said projection to hold the pawl out of engagement with the teeth on the drum, said trigger nose having an inclined surface which, if a pull should again be exerted upon the trigger after the pawl has moved into engagement with the teeth, will coöperate with a corresponding surface on the projection to hold the pawl all the more firmly in engagement with the teeth.

6. In a submarine mine comprising a flotation chamber constituting the mine proper, a toothed anchor cable drum and a plummet for determining the depth at which the flotation chamber is to be anchored beneath the surface of the water, the combination of a spring controlled pawl for engaging with the teeth of said drum, a lateral pin on said pawl, a movable member normally lying in the path of said pin, but moved out of the path when the drum has made a predetermined number of revolutions, a spring controlled trigger which is connected to the plummet and has a nose for engaging with part of said pin to hold the pawl out of engagement with the teeth on the drum, said trigger nose having an inclined surface which, if a pull should again be exerted upon the trigger after the pawl has moved into engagement with the teeth, will coöperate with a corresponding surface on the pin to hold the pawl all the more firmly in engagement with the teeth.

In testimony whereof, I affix my signature.

THOMAS KEPPEL NORTH.
